UNITED STATES PATENT OFFICE.

ARTHUR A. STEWART, OF LYNCH, NEBRASKA.

MAIL CARRIER.

Application filed September 28, 1921. Serial No. 503,703.

To all whom it may concern:

Be it known that I, ARTHUR A. STEWART, a citizen of the United States, residing at Lynch, in the county of Boyd and State of Nebraska, have invented certain new and useful Improvements in Mail Carriers, of which the following is a specification.

This invention has for its object the provision of a simple, inexpensive and efficient device whereby rural delivery postmen may be enabled to carry a large bundle of mail in a compact form and may readily withdraw from the bundle one or more pieces of mail matter for delivery to an addressee. The invention seeks to provide a device which may be readily adjusted to the quantity of mail to be carried and which will be light and easily manipulated and which, when not in use, may be folded into compact form so as to be placed in a small compass out of the way.

One embodiment of my invention is illustrated in the accompanying drawings, in which—

25 Figure 1 is a perspective view of the improved device;

Fig. 2 is an edge view of the same, Fig. 1 showing the device arranged to receive mail matter and Fig. 2 showing it folded for storage or transportation;

Fig. 3 is an enlarged detail sectional elevation.

Fig. 4 is an enlarged detail perspective view of the latch.

35 In carrying out my invention, I employ a pair of standards 1 which may conveniently be of wood and will preferably be of rectangular cross section. Through the lower ends of these posts or standards 1, I insert

40 a bolt or rod 2 which constitutes the pintle for hinges 3, the said hinges having their leaves secured to base plates 4. When the device is set up for use to receive mail matter, the plates 4 are extended in horizontal alignment, as shown in Fig. 1 and the mail is placed upon the plates between the standards 1. When the device is not to be used, the plates 4 may be easily folded toward each other, as shown in Fig. 2, so that an

50 economy of space will be effected. To aid in holding the standards 1 in an upright position when mail matter is being placed between the same, I provide a spring 5 having its opposite ends secured to one of the standards and one of the plates 4, respectively, as shown in Fig. 1. The spring 5

may be of any convenient or preferred form. The form illustrated is so tempered that it will be inactive when the terminals are at right angles so that the force of the spring 60 will come into play only when the angle of the base plate and the standard is changed, the tension of the spring being increased by compression when the standard is moved in one direction and increased by expansion 65 when the spring tends to move in the opposite direction.

Slidably mounted upon the standards 1 is an inverted U-shaped frame which may conveniently be formed of metal of a U-shaped 70 cross section, the legs 6 fitting slidably over the standards 1 and the arched member 7 connecting the upper ends of the legs constituting a handle whereby the device may be easily handled, as will be readily understood. The inner web or back of the upper U-shaped member is constructed with longitudinal slots 8 adapted to receive the ends of a bolt 9 fitted in the upper ends of the standard 1, and nuts 10 mounted on the 80 said bolt are turned home against the web of the frame so as to secure the upper inverted U-shaped member at any desired height relative to the standards. I am thus enabled to very easily and quickly adjust 85 the height of the frame to the quantity of mail matter which is to be placed therein. Across the outer open side of the upper frame, I secure spaced pins or rivets 11 which are adapted to be engaged by spring-controlled latches 12 mounted on the ends of a follower 13 which is adapted to bear upon the top of the bundle of letters or packages placed in the device. This follower preferably is an open rectangular 90 frame fitted loosely around the upper frame of the device so as to move freely vertically thereon. On the under side of the follower at the opposite sides of the upper frame, I provide rollers 14 which are adapted to bear 100 upon the bundle of mail matter so that, while the said matter will be effectually held to the base plates 4, the top piece or any intermediate piece may be readily withdrawn without requiring the pressure upon 105 the bundle to be relieved. It will be readily understood that after the bundle of letters or packages has been placed upon the base plate 4 between the standards and the upper adjustable frame of the device, the follower 110 is pushed manually down onto the bundle so that the rollers 14 will rest there-

on. The latches 12 will ride readily over the pins or rivets 11 during the downward movement of the follower and will engage under the respective pins or latches respectively, as shown in Fig. 3, so that, when the desired pressure has been placed upon the bundle, the free upward movement of the follower will be prevented and the mail will be securely held. If it be desired to remove the follower, the latches 12 may be easily released in an obvious manner so as to permit the follower to be raised along and from the upper adjustable frame. As the bundle of mail matter is decreased by reason of deliveries therefrom, the follower may be pushed downwardly so as to maintain the compact condition of the bundle, as will be readily understood.

Having thus described the invention, what is claimed as new is:

1. A device for the purpose set forth comprising a pair of standards, a bolt inserted

through the lower ends of said standards, hinges carried by said bolt, base plates disposed at opposite sides of the said bolt and secured to said hinges, and a follower supported on the standards.

2. A device for the purpose set forth comprising a base plate, standards rising therefrom, legs fitted to and embracing said standards and having open outer sides and longitudinally slotted inner sides, spaced stops extending across the outer open sides of the said legs, securing devices carried by the standards and passing through the longitudinally slotted inner sides of the legs, a follower mounted upon the said legs and extending between the same, and latches mounted on the ends of the follower and adapted to engage the said stops in the outer open sides of the legs.

In testimony whereof I affix my signature.

ARTHUR A. STEWART. [L.S.]
